[57] CLAIM

The ornamental design for combined TV remote with storage and recharge receptacle, as shown and described.

DESCRIPTION

FIG. 1 is a perspective view of a combined TV remote with storage and recharge receptacle, showing my new design, showing broken away for ease of illustration;

FIG. 2 is a reduced perspective view thereof, showing the design in use, the broken line showing of the TV console is for illustrative purposes only, and forms no part of the claimed design;

FIG. 3 is a top plan view thereof;

FIG. 4 is a rear elevational view thereof;

FIG. 5 is a right side elevational view thereof, the left side being a mirror image thereof;

FIG. 6 is front elevational view thereof;

FIG. 7 is a bottom plan view thereof;
